Primary Examiner — Kendra Leslie Hamilton*(74) Attorney, Agent, or Firm* — MH2 Technology Law Group LLP(57) **CLAIM**

The ornamental design for a teat for feeding bottles, as shown and described.

DESCRIPTION

FIG. 1 is a front elevational view of a teat for feeding bottles showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and,

FIG. 7 is a top, right perspective view thereof.

The broken lines in FIG. 6 depict portions of the teat for feeding bottles that form no part of the claimed design.
